COUNTER DISPLAY CASE

Peter Schladermundt, Bronxville, and William H. Dennerlein, Whitestone, N. Y., assignors to The Gillette Company, Boston, Mass., a corporation of Delaware

Application January 5, 1952, Serial No. 17,958

Term of patent 14 years

(Cl. D80—11)

To all whom it may concern:

Be it known that we, Peter Schladermundt and William H. Dennerlein, both citizens of the United States and residing respectively at Bronxville, New York, and Whitestone, New York, have invented a new, original, and ornamental Design for a Counter Display Case, of which the following is a specification, reference being had to the accompanying drawing, forming a part hereof, wherein:

Fig. 1 is a front perspective view of a counter display case showing our new design;

Fig. 2 is a rear perspective view in an open position;

Figs. 3, 4, 5 and 6 are respectively plan, front elevational, rear elevational, and side elevational views of the display case shown in Fig. 1 but on a somewhat reduced scale.

We claim:

The ornamental design for a counter display case, substantially as shown.

PETER SCHLADERMUNDT.
WILLIAM H. DENNERLEIN.
